UNITED STATES PATENT OFFICE.

ALBERT M. AHERN, OF ST. LOUIS, MISSOURI.

COMBINED SHIPPING TAG AND ENVELOPE SHEET.

Application filed November 10, 1919. Serial No. 336,911.

To all whom it may concern:
 Be it known that I, ALBERT M. AHERN, a citizen of the United States of America, a resident of the city of St. Louis, in the State 5 of Missouri, have invented certain new and useful Improvements in Combined Shipping Tags and Envelope Sheets, of which the following is a full, clear, and exact description, reference being had to the accompanying 10 drawings, forming a part of this specification.

My invention relates to a shipping tag so formed as to constitute also an envelope sheet, which may be used as a letter or information sheet, or be folded to form an enclosure for letters or other objects. The invention has further as one of its objects to provide an identification section initially forming a part of the shipping tag and envelope 15 sheet, but which is made detachable therefrom and is intended to receive memoranda relating to the contents of a package to which the tag and envelope sheet in a closed condition is attached, to serve as a medium for identifying the consignor and 20 consignee or giving other information respecting the package, in the event of loss or mutilation of the shipping tag and envelope.

Fig. I is a plan of the rear side of my tag and envelope sheet as it appears before folding.

Fig. II is a plan of the rear side of the tag and envelope sheet when its end sections have been folded.

Fig. III is a plan of the tag and envelope sheet as it appears when folded, except for the securing of the sealing flap.

Fig. IV is a front plan of the tag and envelope sheet, in folded and closed condition.

My tag and envelope sheet comprises a plurality of sections adapted to be folded on defined lines to form an enclosure. The portion of the sheet which is to constitute a tag is located centrally of the sheet and includes 45 a front section 1 and a rear section 2, the latter being foldable onto the front section on a line *a*. At the ends of the tag sections 1 and 2 are flap sections 3 and 4, foldable on lines *b* and *c* so that they will overlie the rear faces of the tag sections 1 and 2, as seen in Fig. II. The end flap section 4 is made of sufficient dimensions to overlap the end flap section 3 and is adapted to be sealed to the latter, and with this object in view said section 50 4 is preferably provided with a gummed

surface 5, which may be moistened to cause it to adhere to the end flap section 3.

One of the end flap sections, preferably that designated 4, has detachably secured thereto an identification tab 6, preferably in 60 the form of a tag, which is adapted to be severed from the flap section prior to the closure of the combined tag and envelope sheet.

One of the tag sections 1, 2 is provided with a sealing flap 7, preferably gummed, 65 which is adapted to be secured to the other tag section when the tag and envelope sheet have been completely folded, as will herein-after appear.

In the use of my tag and envelope sheet, 70 the device is made ready for service in the following manner. Before folding, or completely folding, the tag and envelope sheet, the identification tab 6 is separated from the remainder of the sheet to be made use of in 75 a manner to be hereinafter explained, and the sheet is then folded as follows:

The folding operation involves, first, the folding of the end flap section 3 on the line *b*, so that it will overlie the adjacent ends of the tag sections 1 and 2. The end flap section 4 is then folded on the line *c* to overlie the other ends of the tag sections and is preferably adhered to the flap section 3 through the medium of the gummed surface 5. A partial enclosure is thereby produced. The back tag section 2, with portions of the flap sections 3 and 4 overlying it, is then folded on the line *a* and brought against the front tag section 1, thereby completing the 90 enclosure except for the application of the sealing flap 7, which, upon being folded over onto, and secured to, the back tag section, completes the closure of the sheet.

The tag sections 1 and 2 are provided at their ends with perforations 8, preferably reinforced by perforated disks 9 secured to said sections, and the end flap section adjacent to the perforated ends of the tag sections is provided with perforations 10, which 95 register with the perforations 8 when the tag and envelope sheet is folded. A cord or other attaching means may be readily passed through the registering perforations to serve as a means for securing the tag and envelope sheet to a package to be shipped.

The tab 6 is preferably provided with a perforation 11 through which a cord or other fastening means may be inserted, and this tab is intended to be supplied with shipping 100 110

instructions or other memoranda it may be desired to place thereon, and is intended to be enclosed within the package to be shipped, preferably being secured to the contents so that it will not become separated therefrom in the event of the wrapper or other enclosure of the package becoming destroyed.

I claim:

In a tag and envelope sheet having complementary central tag sections with indicia on one of said tag sections for the addressee

and addressor and end sections foldable onto said tag sections, of a detachable identification tag section, having indicia thereon for the addressee and addressor, forming an extension of one of said end sections and in longitudinal alignment with one of said complementary tag sections.

In testimony that I claim the foregoing I hereunto affix my signature.

ALBERT M. AHERN.
